[57] CLAIM

The ornamental design for a vehicle body, as shown and described.

DESCRIPTION

FIG. 1 is a front perspective view illustrating a vehicle body constructed in accordance with the teachings of the present invention.

FIG. 2 is a left side view thereof, it being understood that the side opposite to that shown is a substantial mirror image thereof.

FIG. 3 is a rear perspective view thereof.

FIG. 4 is a front view thereof; and,

FIG. 5 is a rear view thereof.

It will be understood that the top of the vehicle is plain and unornamented. It will also be understood that the broken line showing of tires and an exhaust pipe is illustrative only and forms no part of the subject invention.
